[57] ABSTRACT

Acyloxydodecatriene is produced by reacting an octatriene, a butadiene and a carboxylic acid in the presence of a catalytic amount of a divalent palladium compound selected from the group consisting of organic acid salts of palladium (II), chelate complexes of palladium (II) and palladium nitrate.

10 Claims, No Drawings

**PROCESS FOR PRODUCING
ACYLOXYDODECATRIENES**

RELATED APPLICATION

This application is related in subject matter to co-pending U.S. Pat. application Ser. No. 207,649, filed Dec. 13, 1971, of the same title and by the same inventors.

BACKGROUND OF THE INVENTION

1. Field Of The Invention

This invention relates generally to a process for producing acyloxydodecatrienes. More particularly, this invention relates to a process for producing acyloxydodecatrienes by the use of octatriene, butadiene and a carboxylic acid as the reactants.

In this specification, the term "butadiene" is intended to include both 1,3-butadiene and the lower alkyl substituted 1,3-butadienes, and the term "octatriene" is intended to include both 1,3,7-octatriene and the lower alkyl substituted 1,3,7-octatrienes, which are substituted on the 2-8 carbon atom positions.

2. Description Of The Prior Art

Acyloxydodecatrienes are well known triene derivatives which have found important industrial utilization in a variety of fields. In studying the oligomerization reactions of butadiene, it had been found that the reaction of butadiene, carboxylic acid and octatriene can be quite effectively catalyzed by the use of certain palladium compounds.

SUMMARY OF THE INVENTION

Accordingly, it is one object of this invention to provide a process for producing useful acyloxydodecatrienes in an industrially effective manner.

This and other objects of this invention, as will hereinafter become more readily apparent, can be attained by reacting an octatriene, a butadiene, and a carboxylic acid in the presence of a catalytic amount of a divalent palladium compound selected from the group consisting of organic acid salts of palladium (II), chelate complexes of palladium (II) and palladium nitrate.

**DETAILED DESCRIPTION OF PREFERRED
EMBODIMENTS**

The octatriene used as a reactant herein may be 1,3,7-octatriene or a lower alkyl substituted 1,3,7-octatriene having lower alkyl groups at the 2-8 positions and preferably at the 2-7 position. It is especially preferable to use an octatriene having the formula:

wherein each R_1 may be the same or different, and each may represent hydrogen or an alkyl group. Suitable examples of said formula I include 1,3,7-octatriene, 2,7-dimethyl-1,3,7-octatriene, etc.

The carboxylic acids used as reactants in this process are those compounds having the formula:

(II)

wherein R_2 represents an alkyl group, cycloalkyl group, aryl group or aralkyl group and which contains two to 20 carbon atoms. Suitable examples of compounds having the formula II include the aliphatic carboxylic acids, e.g., acetic acid, propionic acid, lactic acid, isovaleric acid, pivalic acid; alicyclic carboxylic acids, e.g., cyclohexyl carboxylic acid; and aromatic carboxylic acid, e.g., benzoic acid. It is most preferable to use a lower aliphatic carboxylic acid, e.g., acetic acid and propionic acid, and especially acetic acid.

The reaction of this invention can be shown by the following schematic, when the compound having the formula I is used as the octatriene:

In the reaction of this invention, acyloxyoctadienes having the following formulae (IV, V and VI) are produced as byproducts:

The catalysts used for the process of this invention are divalent palladium compounds selected from the group consisting of organic acid salts of palladium (II), chelate complexes of palladium (II) and palladium nitrate. The organic acid salts of palladium (II) can be divalent palladium carboxylate, such as palladium acetate, palladium propionate, palladium benzoate, or the like. The chelate complexes of palladium (II) can be chelated divalent palladium compounds such as palladium acetylacetone, palladium acetoacetic ester complex, or the like. The palladium compound may be used in amounts of 1×10^{-4} - 1.0 gram atom, preferably 1×10^{-3} - 1×10^{-2} gram atom, as palladium atom per 1 mole of octatriene.

The usable quantitative ratios of the octatriene, the butadiene and the carboxylic acid can be selected over wide ranges. However, the selectivity of the reaction for acyloxydodecatrienes or acyloxyoctadienes will vary depending upon the quantitative ratio of the three reactants. In order to maximize the yield of acyloxydodecatrienes, it is preferable to use a molar ratio of the three reactants of 1.0 : 0.5 - 5.0 : 0.1 - 1.0 and preferably 1.0 : 1.0 - 2.0 : 0.2 - 0.5 of octatriene:butadiene:carboxylic acid. When the molar ratio of butadiene is low, the reaction will be selective toward acyloxydodecatrienes, and higher molar ratios will shift the equilibrium toward acyloxyoctadienes.

When the palladium compound is mixed with certain other additives, such as the phosphines, especially triphenylphosphine, it has a tendency to decrease the formation of acyloxydodecatrienes. Therefore, the use of such phosphines is not desirable if high yields of acyloxydodecatrienes are desired.

The reaction can be effected without a solvent medium. However, it is possible to use an inert medium. Typical mediums include the aromatic compounds, e.g., benzene, toluene; ethers, e.g., diethylether, tetrahydrofuran, dioxane; esters, e.g., ethyl acetate; ketones, e.g., acetone.

The reaction temperature may be 0° – 150°C., and preferably 40° – 120°C. The reaction velocity is low at lower temperatures, while byproducts of 4-vinylcyclohexene and dodecatetraene, etc. are produced, and the catalytic activity is decreased at higher temperatures. The reaction pressure may be 1 – 50 atm., and preferably 5 – 25 atm., and the reaction can be carried out under the pressure of an inert gas, e.g., nitrogen or argon.

The reaction mixture may include acyloxydodecatriene, acyloxyoctadiene, unreacted raw materials, medium and catalyst. Following the reaction, the reaction products may be separated and the unreacted reactants recovered by distillation.

An equilibrium relationship exists between the 1-acyloxydodecatriene and the 3-acyloxydodecatriene in the reaction system. Accordingly, when one type of isomer is supplied to the reaction system, the formation of the same type of isomer will be decreased and the formation of the other type of isomer will be increased. It is therefore desirable to add a 3-acyloxydodecatriene when the formation of a 1-acyloxydodecatriene is desired, and to add a 1-acyloxydodecatriene when the opposite result is desired. The amount of such isomer which may be added to the reaction is not limited and can be more or less than the equilibrium amount at the particular reaction condition. When the amount of one isomer added to the reaction system is greater than the equilibrium amount, the formation of the same type of the adduct will be decreased, and simultaneously a portion of the isomer added will be isomerized to the opposite type of isomer until equilibrium is reached between the two isomers at the reaction conditions. The desired isomer can therefore be selectively and simply produced in an industrially advantageous manner.

The acyloxydodecatrienes prepared by the process of this invention may be the esters of long chain unsaturated alcohols having a straight chain structure, as stated above, which are useful for producing long chain unsaturated alcohols, long chain unsaturated carboxylic acids, synthetic drying oils and other useful derivatives.

In the process of this invention, an acyloxyoctadiene is produced as a reaction byproduct, but the acyloxyoctadienes can be easily separated from the acyloxydodecatrienes by distillation. Moreover, acyloxyoctadienes can be used as starting materials for the production of a variety of derivatives. Accordingly, the by-production of acyloxyoctadienes will not cause any severe difficulty.

The main starting material for the process of this invention, the octatrienes, can be easily produced by dimerization of butadiene or isoprene. Accordingly, the process of this invention is quite advantageous from an industrial point of view.

Having generally described the invention, a further understanding can be attained by reference to certain specific examples which are provided herein for purposes of illustration only and are not intended to be limiting in any manner unless otherwise specified.

The abbreviations used in the examples will have the following meanings:

ADT:	acyloxydodecatrienes
1-ADT:	1-acyloxy-2,7,11-dodecatrienes
3-ADT:	3-acyloxy-1,7,11-dodecatrienes
AOD:	acyloxyoctadienes
1-AOD:	1-acyloxy-2,7-octadienes
3-AOD:	3-acyloxy-1,7-octadienes
3'-AOD:	3-acyloxy-1,6-octadienes
D rate:	molar % of ADT to total amount of ADT and AOD in the resulting product;
n rate:	percent of 1-ADT or 1-AOD to ADT or AOD.

EXAMPLE 1

0.3 m mole of palladium acetate was dissolved in 0.2 mole of 1,3,7-octatriene under an argon atmosphere. This solution and 0.1 mole of acetic acid were charged to a 100 ml. microbomb, which is designed to be shaken in an oil bath. The microbomb was purged with nitrogen gas and 0.2 mole of butadiene was added to the microbomb. The contents were heated to 80°C. and the reaction was carried out for 11 hours at said temperature. After the reaction, the microbomb was cooled to room temperature, and unreacted butadiene was recovered and the resulting products were analyzed. The conversion of acetic acid was 71 percent and the resulting products were 4.0 g. of 1-acetoxy-2,7-octadiene (1-AOD), 0.9 g. of 3-acetoxy-1,7-octadiene (3-AOD) and 3-acetoxy-1,6-octadiene (3'-AOD) and 6.9 g. of 1-acetoxy-2,7,11-dodecatriene (1-ADT), and 2.5 g. of 3-acetoxy-1,7,11-dodecatriene (3-ADT). Accordingly, the D rate was 59 percent and the n rate for ADT was 74 percent.

1-acetoxy-2,7,11-dodecatriene and 3-acetoxy-1,7,11-dodecatriene, respectively, having the following characteristics, were found. 1-acetoxy-2,7,11-dodecatriene is a colorless liquid having a boiling point of 115° – 120°C./1 mmHg and the analytical results thereof are as follows:

a. Elementary analysis: C₁₄H₂₂O₂

	C(%)	H(%)
Calculated	75.63	9.98
Analysis	75.36	9.94

b. Infrared spectra:

absorption bands at 3,060, 2,960, 2,910, 2,850, 1,735, 1,670, 1,638, 1,415, 1,360, 1,240, 990, 970, 910 cm⁻¹

c. Nuclear magnetic resonance spectra:

absorption bands at

4.2–4.7 (multiple lines)

4.7–5.2 (multiple lines)

5.4–5.6 (double lines)

7.8–8.1 (multiple lines)

8.0 (single line) and 8.3–8.6 (multiple lines) of τ value.

d. Mass spectra:

peaks at 43 (CH₃CO), 61 (CH₃C(OH)₂), and 162 (C₁₂H₁₈) of M/e value.

Molecular weight is 222 (CH₃COOC₁₂H₁₈)

e. Refractive index:

$$n_D^{21.5} = 1.4649$$

3-acetoxy-1,7,11-dodecatriene is a colorless liquid having a boiling point of 95°–100°C./1 mmHg and the analytical results thereof are as follows:

a. Elementary analysis: $C_{14}H_{22}O_2$

	C (%)	H (%)
Calculated	75.63	9.98
Analysis	75.95	10.04

b. Infrared spectra:

absorption bands at

3,060, 2,960, 2,910, 2,850, 1,735, 1,670, 1,638, 1,415, 1,360, 1,240, 990, 970, 910 cm^{-1}

c. Nuclear magnetic resonance spectra

absorption bands at

4.0–4.7 (multiple lines),

4.7–5.2 (multiple lines),

7.8–8.1 (multiple lines),

8.0 (single line) and 8.4–8.6 (multiple lines) of τ value.

d. Mass spectra:

Peaks at 43 (CH_3CO), 61 ($\text{CH}_3\text{C}(\text{OH})_2$), 162 ($\text{C}_{12}\text{H}_{18}$) of M/e value.

Molecular weight is 222 ($\text{CH}_3\text{COOC}_{12}\text{H}_{18}$)

e. Refractive index:

$$n_D^{21.5} = 1.4638$$

EXAMPLES 2 – 6

The reaction was repeated in accordance with the process of Example 1, except using the starting materials and reaction conditions as stated in Table I, wherein the symbols are as follows:

AcOH:	acetic acid
nOT:	1,3,7-octatriene
BD:	butadiene
Pd(OAc) ₂ :	palladium acetate
Pd(OPr) ₂ :	palladium propionate

TABLE I

Ex. No.	Cat. type	Start material					
		m mole	AcOH	nOT	BD	Reac- tion temp. (°C.)	Reac- tion time (hours)
2	Pd(OAc) ₂	0.3	0.1	0.2	0.2	80	6
3	Pd(OAc) ₂	0.3	0.05	0.2	0.2	80	7
4	Pd(OAc) ₂	0.1	0.1	0.2	0.2	110	6
5	Pd(OAc) ₂	0.1	0.05	0.1	0.15	60	24
6	PD(OPr) ₂	0.1	0.05	0.1	0.17	110	5

The results of the reaction of each example are shown in Table II, wherein each example number corresponds to those of Table I.

TABLE II

Ex. No.	Conver- sion acetic acid (%)	AOD		ADT		
		Yield (g)	n rate (%)	Yield (g)	n rate (%)	D rate (%)
2	50	3.0	86	7.1	72	64
3	86	2.3	79	6.5	77	68
4	18	0.9	64	2.8	69	69
5	73	2.8	91	4.4	71	55
6	54	2.0	74	3.4	69	56

EXAMPLE 7

0.2 m mole of palladium acetate, 0.074 mole of 2,7-dimethyl-1,3,7-octatriene and 0.05 mole of acetic acid were charged to a 100 ml. microbomb, and then, 0.15 mole of butadiene was added with pressured nitrogen gas, and the contents were heated to 110°C. The reaction was carried out at 110°C. for 5 hours. After the reaction, the microbomb was cooled to room temperature, and unreacted butadiene was recovered.

According to analysis of the resulting products by gas chromatography, conversion of acetic acid was 26 percent, and the resulting products were 0.8 g. of 1-acetoxy-2,7-octadiene (1-AOD), 0.5 g. of 3-acetoxy-1,7-octadiene (3-AOD), and 3-acetoxy-1,6-octadiene (3'-AOD), 1.0 g. of 1-acetoxy-6,11-dimethyl-2,7,11-dodecatriene (1-ADT) and 0.4 g. of 3-acetoxy-6,11-dimethyl-1,7,11-dodecatriene (3-ADT). Accordingly, the D rate was 48 percent, and the n rate of ADT was 71 percent.

EXAMPLE 8

0.1 m mole of palladium acetate, 0.1 mole of 1,3,7-octatriene and 0.05 mole of propionic acid were charged to a 100 ml. microbomb, and then 0.15 mole of butadiene was added with pressured nitrogen gas. The reaction was carried out at 110°C. for 5 hours. After the reaction, the resulting products were analyzed in accordance with the process of Example 7.

The conversion of propionic acid was 24 percent and the resulting products were 0.65 g. of 1-propionyloxy-2,7-octadiene (1-AOD), 0.33 g. of 3-propionyloxy-1,7-octadiene (3-AOD) and 3-propionyloxy-1,6-octadiene (3'-AOD), 1.18 g. of 1-propionyloxy-2,7,11-dodecatriene (1-ADT) and 0.38 g. of 3-propionyloxy-1,7,11-dodecatriene (3-ADT). Accordingly, the D rate was 55 percent and the n rate of ADT was 76 percent.

EXAMPLE 9

0.1 m mole of palladium acetate, 0.1 mole of 1,3,7-octatriene and 0.05 mole of benzoic acid were charged to a 100 ml. microbomb, and then 0.15 mole of butadiene was added with pressured nitrogen gas. The reaction was carried out at 110°C. for 5 hours, and the resulting products were analyzed in accordance with the process of Example 7.

The conversion of benzoic acid was 21 percent, and the resulting products were 0.81 g. of 1-benzyloxy-2,7-octadiene (1-AOD), 0.34 g. of 3-benzyloxy-1,7-octadiene (3-AOD), and 3-benzyloxy-1,6-octadiene (3'-AOD), 1.20 g. of 1-benzyloxy-2,7,11-dodecatriene (1-ADT) and 0.36 g. of 3-benzyloxy-1,7,11-dodecatriene (3-ADT). Accordingly, the D rate was 52 percent and the n rate of ADT was 77 percent.

EXAMPLE 10

0.1 m mole of palladium acetylacetone was dissolved in 0.1 mole of 1,3,7-octatriene in a nitrogen gas atmosphere and the solution was charged with 0.05 mole of acetic acid in a 100 ml. microbomb. The microbomb was purged with nitrogen gas and 0.13 mole of butadiene was fed and the contents were heated to 110°C. The reaction was carried out at 110°C. for 5 hours. After the reaction, the microbomb was cooled to room temperature and unreacted butadiene was recovered.

According to analysis of the resulting products by gas

chromatography, conversion of acetic acid was 61 percent and the resulting products were 1.35 g. of 1-acetoxy-2,7-octadiene (1-AOD), 0.45 g. of 3-acetoxy-1,7-octadiene (3-AOD) and 3-acetoxy-1,6-octadiene (3'-AOD), 2.96 g. of 1-acetoxy-2,7,11-dodecatriene and 1.34 g. of 3-acetoxy-1,7,11-dodecatriene (3-ADT). Accordingly, the D rate was 64 percent, the n rate of AOD was 75 percent and the n rate of ADT was 69 percent.

EXAMPLE 11

0.04 m mole of palladium nitrate was dissolved in 0.10 mole of 1,3,7-octatriene and 0.05 mole of acetic acid in a nitrogen gas atmosphere and the solution was charged to a 100 ml. microbomb. The microbomb was purged with nitrogen gas and 0.248 mole of butadiene was charged. The reaction was carried out at 110°C. for 2 hours. After the reaction, the microbomb was cooled to room temperature and unreacted butadiene was recovered.

According to analysis of the resulting products by gas chromatography, conversion of acetic acid was 45 percent, and the resulting products were 0.78 g. of 1-acetoxy-2,7-octadiene (1-AOD), 0.63 g. of 3-acetoxy-1,7-octadiene (3-AOD) and 3-acetoxy-1,6-octadiene (3'-AOD), 2.93 g. of 1-acetoxy-1,7,11-dodecatriene (1-ADT) and 0.56 g. of 3-acetoxy-1,7,11-dodecatriene (3-ADT). Accordingly, the D rate was 65 percent, the n rate of AOD was 55 percent, and the n rate of ADT was 84 percent.

EXAMPLES 12 - 15

The reaction was carried out by adding either of 1-acyloxy-2,7,11-dodecatriene or 3-acyloxy-1,7,11-dodecatriene to the reaction system. 6 g. of acetic acid, 10.8 g. of 1,3,7-octatriene, 16.2 g. of butadiene, catalyst and either of 1-acyloxy-2,7,11-dodecatriene or 3-acyloxy-1,7,11-dodecatriene were charged to a 100 ml. autoclave (SUS-32 type) and the reaction was carried out at 100°C. for 5 hours. After the reaction, unreacted butadiene was recovered, and the resulting products were analyzed by gas chromatography.

The reaction condition and results are shown in Table III.

Having now fully described the invention, it will be apparent to one of ordinary skill in the art that many changes and modifications can be made thereto without departing from the spirit or scope of the invention.

What is claimed as new and desired to be secured by Letters Patent is:

1. A process for producing an acyloxydodecatriene which consists essentially of admixing and reacting 1,3,7-octatriene or a lower alkyl substituted 1,3,7-octatriene having the general formula:

wherein each R₁ may be the same or different and may be selected from the group consisting of hydrogen and a lower alkyl group; butadiene; and a carboxylic acid having two to 20 carbon atoms and having the general formula:

wherein R₂ is an alkyl group, a cycloalkyl group, an aryl group, or an aralkyl group, in the presence of a catalytic amount of a catalyst consisting essentially of a divalent palladium compound selected from the group consisting of organic acid salts of palladium (II), chelate complexes of palladium (II) and palladium nitrate wherein the molar ratio of the octatriene : butadiene : carboxylic acid is 1.0 : 0.5 - 5 : 0.1 - 1.0.

2. The process of claim 1, wherein said reaction is effected at a temperature of 10°C. - 200°C. and a pressure of 1 - 50 atmospheres.

3. The process of claim 1, wherein 1 × 10⁻⁴ - 1.0 gram atom of divalent palladium component per mole of 1,3,7-octatriene or lower alkyl substitute is used as the catalyst.

4. The process of claim 1, wherein 1-acyloxydodecatriene or 3-acyloxydodecatriene is added to the reaction mixture to cause the preferential formation of the opposite isomer.

5. The process of claim 1, wherein the catalyst is palladium acetate, palladium acetylacetone, or palladium nitrate.

6. The process of claim 1, wherein the carboxylic acid is acetic acid, propionic acid or benzoic acid.

7. The process of claim 1, wherein 1,3,7-octatriene, butadiene and acetic acid are reacted in a molar ratio of 1.0 : 0.5-5.0 : 0.1-10 at 40-120°C. in the presence of a catalyst of a divalent palladium compound selected from the group consisting of organic salts of palladium (II), chelate complexes of palladium (II) and palladium nitrate, and acetoxydodecatrienes are recovered from the reaction product.

8. The process of claim 7, wherein the catalyst is palladium acetyl acetone, palladium acetate or palladium nitrate.

TABLE III

Ex. No.	Catalyst		Additive		Products (g.)				Formed Products		
	type	g.	type	g.	AOD	3-ADT	1-ADT	D rate (%)	3-ADT	1-ADT	Formed D rate (%)
12	Pd(acac) ₂	0.03	—	—	4.9	1.8	4.0	69	1.8	4.0	69
13	"	0.03	3-ADT	1.7	3.5	1.8	4.9	73	0.1	4.9	98
